UNITED STATES PATENT OFFICE.

AUGUST DANIELSSON, OF LONDON, ENGLAND.

DEVICE FOR DRAWING PARALLEL LINES.

1,249,599.

Specification of Letters Patent.

Patented Dec. 11, 1917.

Application filed March 25, 1916. Serial No. 86,736.

To all whom it may concern:

Be it known that I, AUGUST DANIELSSON, a subject of the King of England, residing at London, England, have invented certain

5 Improvements in Devices for Drawing Parallel Lines, of which the following is a specification.

The present invention relates to a device 10 for facilitating the drawing of parallel lines and consists in the combination with two members, for instance those of an ordinary parallel ruler, of two vertical finger-operated keys mounted on such members, one on each, and of means acting on the two members 15 in such a fashion that an alternate vertical pressure on the keys brings about the step-by-step movement of the ruling device.

The invention is illustrated by way of example in the accompanying drawings,

20 Figure 1 representing a partial plan of a parallel ruler fitted with the device.

Fig. 2, a central section through one of the keys viewed in the direction of the arrow, *a*,

25 Fig. 3, a similar section of the other key, and

Fig. 4, an elevation of one of the keys seen in the direction of the arrow *b*.

Fig. 5 is a view of one of the details of the device.

30 Fig. 6 is a plan of a device of a modified construction, and

Fig. 7, a sectional side view of a key showing a modified construction of the latter.

1 and 2 are the blades of an ordinary ruler 35 and they are fitted with keys 3 and 4 which are slidably held in hollow uprights 5 secured to the blades 1 and 2. Two arms 6 and 7 are connected respectively to the

40 blades 2 and 1, the free end of each arm being guided in a slit made for the same in the key support of the opposite blade. Wedges

8 and 9, formed respectively on the arms 6 and 7, are adapted to move in slits 10 made for the same in the uprights 5. The keys co-

45 operate with the inclined surfaces of these wedges for forcing the latter out of the slits 10, and the arrangement is such that a depression of the key 3 pushes the arm 6 and the blade 2 backward, and a depression of

50 the key 4 pulls the arm 7 and the blade 1 in the same direction. The keys are so ar-

ranged that they can be operated by two fingers of the same hand, and the step-by-step movement of the ruler can thus be easily

55 effected by one hand, the keys being simply alternately depressed. The pressure on one

key steadies the blade to which it is connected while the other blade is being moved.

A lug 11 on the free end of the arm 6 limits the movement of the rear blade 2 by 60 abutment against the upright 5. The movement of the blade 1 is limited by a screw spindle which abuts against the other upright and which can be adjusted for varying the spacing of the steps. A forked piece 13 65 secured to the arm 7, holds the screw spindle so that it can move freely in a longitudinal direction, a milled nut 14, mounted on the spindle and held in the fork of the piece 13 so that it can be readily turned with a finger, 70 being employed for varying the position of the spindle. A plate 15, connected to the outer end of the spindle 12, moves over the arm, as shown in Fig. 5, and prevents the spindle from rotating about its axis. The 75 plate, moreover, indicates on a scale 16 on the arm 7 the spacing of the steps.

It is evident that a spring, for instance 17 (Fig. 6), may be employed for moving one of the members, in which case the key of the 80 other member simply consists of a rigid post 18 on which a finger is placed for holding this member in position while the spring acts. At the subsequent depression of the key 4 the other member is moved up and the 85 spring tensioned or compressed.

The key or keys, instead of acting on an inclined surface may have the movement transmitted to the arm by other means, for instance such as indicated in Fig. 7. The 90 key 19 is here formed with teeth which mesh with a wheel 20 held in the upright 21. The arm 22, which operates like the arms in the previous construction, has a rack which also meshes with the wheel 20 and transmits the 95 motion to the opposite member of the ruling device.

I claim:—

1. A device for facilitating the ruling of parallel lines, comprising the combination 100 with two parallel ruling members connected by parallel links, of two finger-operated keys mounted on such members one on each, and means acting on the two members in such a fashion that an alternate vertical 105 pressure on the keys brings about the step-by-step movement of said members.

2. A device for facilitating the ruling of parallel lines, consisting in the combination 110 with two parallel ruling members connected by parallel links, of two finger-operated keys mounted on such members one on each,

and two arms connected to such members one to each, each arm coöperating with the key of the opposite member in such a fashion that an alternate vertical pressure on the 5 keys brings about the step-by-step movement of said members.

3. A device for facilitating the ruling of parallel lines, comprising the combination with two parallel ruling members connected by parallel links, of two hollow uprights mounted on such members one on each, vertical keys mounted slidably in said uprights, and two arms connected to said members one to each, each arm coöperating with the 10 key of the opposite member in such a fashion that an alternate vertical pressure on the 15 keys brings about the step-by-step movement of said members.

4. A device for facilitating the ruling of parallel lines, comprising the combination with two parallel ruling members connected by parallel links, of two slotted uprights mounted on such members one on each, vertical keys held slidably in said uprights, two 20 arms connected to said members one to each, the free end of each arm being accommodated in a slot in the upright of the opposite member, and wedges formed on the free ends 25

of said arms so as to support and coöperate with said keys in such a fashion that an 30 alternate vertical pressure on the keys brings about the step-by-step movement of said members.

5. A device for facilitating the ruling of parallel lines, comprising the combination 35 with two parallel ruling members connected by parallel links, of two uprights mounted in said members one on each, vertical keys slidably held in said uprights, two arms connected to said members one to each, each 40 arm coöperating with the key of the opposite member in such a fashion that an alternate vertical pressure on the keys brings about the step-by-step movement of said members, a lug formed on one arm so as to limit the 45 separation movement of the members by abutment against the upright of the key by which it is actuated, and an adjustable screw on the other arm arranged so as to limit the closing-up movement of the members 50 by abutment against the opposite upright.

AUGUST DANIELSSON.
